UNITED STATES PATENT OFFICE.

JAMES OTOICHI KINOSITA, OF LOS ANGELES, CALIFORNIA.

ELECTRIC BED-WARMING DEVICE.

1,326,133.

Specification of Letters Patent. Patented Dec. 23, 1919.

Application filed April 8, 1918, Serial No. 227,228. Renewed October 6, 1919. Serial No. 328,945.

To all whom it may concern:

Be it known that I, JAMES OTOICHI KINOSITA, a subject of the Emperor of Japan, residing in the city and county of Los Angeles and State of California, have invented a new and useful Electric Bed-Warming Device, of which the following is a specification.

This invention relates to an improved electric device particularly adapted for production and local application of heat, and the object of the invention is to provide such a device having a capacity for the greatest amount of heat at a minimum cost of production, to provide a device of the character described which is inexpensive to produce, and of which the parts that may be subject to deterioration may be readily obtained at small cost for renewal.

The invention hereinafter described, while particularly adapted for warming a bed, may be used and employed for various analogous purposes and in various analogous ways.

In the drawings, Figure 1 is a front elevation of a heating device embodying my invention; Fig. 2 is a rear end elevation of the same; Fig. 3 is a vertical and longitudinal mid-section of the device; Fig. 4 is a transverse sectional view showing the relative position of the switch and rheostat elements. Fig. 5 is a diagram of the wiring and electric elements.

Referring to the drawings, the device consists essentially of a receptacle 11, preferably constructed of galvanized sheet metal, and having a wooden base 12, and wooden reinforcing elements 13, 14, for stiffening the sheet metal walls. The rear end wall 15, may be of suitable insulating material as shown, and may be made of wood, the inner partition wall 16, is made preferably of fiber, and divides the interior into the heating compartment 17, and the switch compartment 18, and serves to protect the switch and rheostat elements from the heat. Within the heating compartment 17, is mounted the electric bulb receptacle 19, containing the electric bulb 20, adapted to serve as the heating element. The front end of the receptacle is provided with a swing door closure 21, supported by the pivotal bearing elements 22, 23. The bearing elements 22, 23, are relatively off-set relative to one another, so that, when the closure member 21 is swung to closed position, it will be re-

tained in position through contact with the walls of the receptacle, which are formed with unequal sides and angles. In the open position of the closure member, the same is held in position by contact with the walls of the receptacle, particularly the inclined section 24, which is provided with reinforcing element 14. The closure element is thus held in either position by frictional contact. In the open position of the closure element, the electric bulb may be utilized for lighting purposes, the polished sheet metal walls of the receptacle serving as a reflector therefor.

In compartment 18, are contained the resistance coils 25, 26, forming a rheostat for control of the current which is supplied to the electric bulb. From the rheostat 27, the current will pass to the switch 28, which is of simple construction as shown, and provided for four positions, namely: first, a high resistance, including coils 25, 26; second, a medium resistance, including the coil 25, only; third, a low resistance, allowing the flow of the full current; and fourth, off.

The switch 28, consists of a receptacle 29, of insulation, provided with an annular wall 30, on which are mounted spring contact elements 31, connected by wire conduits 32, with the rheostat 27. A revoluble shaft 33, connected to the operating button 34 and provided with an indicator 35, passes through the inner wall 16, and is in contact with the connecting element 36, of the electric bulb receptacle 19. A ratchet member 37, mounted on the shaft, has mounted thereon the contact element 38, connected to the shaft 33, and adapted to register successively with the contact elements 31, except in the "off" position. An indicator plate 39, on the rear wall, denotes the operative positions of the switch. A tension spring 40, interposed between the rear wall, and the ratchet member 37, tends to retain the switch in its operative positions. In the diagram shown in Fig. 5, the positive wire conductor 41 is shown connected to the rheostat, and the negative wire conductor 42 is shown connected to the bulb receptacle 19, the conductors entering through an opening 43 in the rear wall, and conductor 42 passing through an opening 44 in the inner wall. The device is covered with a heavy woven fabric 45, which serves to conserve the heat and particularly adapts the device for the purposes specified.

In the preferred form of the invention,

the device is constructed with a layer 46, of a poor heat conducting material, preferably asbestos. The device may be further modified by constructing a wooden receptacle, or 5 casing, and omitting the sheet metal therein. It may be noted that the reinforcing member 14 extends within the limits of compartment 18, only.

While simple and efficient means are here-
10 in shown for accomplishing the objects of the invention, and the elements shown and described are well adapted to serve the purposes for which they are intended, it is to be understood that the invention is not limited
15 to the precise construction exhibited in the drawings, but that changes, alterations, and modifications, that may fall within the scope of the appended claims, may be made if desired.

20 What is claimed is:

1. The combination with an angular and metallic receptacle having an open end, of closure means for the open end retained in position by frictional contact with the receptacle, a partition wall forming interior switch and heating compartments, an electric bulb in the heating compartment, a switch in the switch compartment, electric bulb contact terminals, a revolute switch
25 member in contact with one of said terminals and projecting through the switch compartment, an exteriorly disposed button to actuate the switch shaft, and electric conductors connected to the switch and the remaining electric bulb terminal, said bulb serving as a lighting medium when the receptacle closure is in open position, and as a heating medium when the closure is in closed position.
- 30 2. A heating device comprising an angular-walled receptacle of sheet metal, and

having an open end, a closure element for the open end adjustable to the open and closed positions and retained in position by frictional contact with the angular walls of 4 the receptacle, an inner transverse partition wall dividing the interior into a heating compartment and a switch compartment, an electric bulb receptacle in the heating compartment and attached to the inner partition 5 wall, a switch receptacle in the switch compartment, a series of spring contact elements carried by the switch receptacle, a revolute shaft coaxial with the switch receptacle, a button to actuate the revolute shaft, a 5 ratchet element fixed to the revolute shaft, a contact plate on the ratchet element, said contact plate being connected with the axial shaft, a contact terminal of the bulb receptacle in constant contact with the axial 6 shaft, a dial plate on the exterior of the angular-walled receptacle, an indicator fixed to the axial shaft and adapted to coöperate with the dial to set the switch, electric supply current conductors, one being secured to 6 the switch and the other to the remaining bulb receptacle contact terminal, an incandescent bulb mounted in the bulb receptacle adapted to supply heat when energized through the switch control, and serving as a 7 lighting means when the receptacle closure is in open position, and a cloth fabric covering conserving the heat generated by the electric bulb within the receptacle. 7

In testimony whereof, I have hereunto affixed my signature this 26th day of March, in the year 1918.

JAMES OTOICHI KINOSITA.
